CONTAINER FOR CIGARETTE PACKAGES

Irving Florman, New York, N. Y., assignor of one-half to J. Spencer Clark, Baltimore, Md.

Application March 13, 1934, Serial No. 715,843

7 Claims. (Cl. 206—41)

The invention relates to cigarette containers and more particularly to containers or protectors for cigarette packages of a size which can easily be carried in the pocket of a consumer.

5 Cigarette containers or protectors for cigarette packages of many kinds have been known. Most of these known containers have, however, been found too expensive because of their complicated construction or impractical because of their 10 weight or bulkiness since they increase the size or the weight of a cigarette package too much to be easily carried in the pocket.

Cigarettes are often sold in light packages of paper or other flexible material. After the removal of some of the cigarettes, the package is easily crushed in the pocket of the user, thereby assuming a crumpled appearance and the cigarettes contained in the package will be broken or bent.

20 The object of my invention is to provide a casing for cigarette packages which will enclose and protect the package from losing its normal shape and the cigarettes in this package from being crushed or bent.

25 Another object is to provide a container for cigarette packages which will securely grip the package so as to hold it in the container, yet without crushing it when a part of the contents have been removed from the package.

30 A further object of the invention is to provide a casing which is light in weight and of simple and cheap construction.

35 Still another object is to provide a casing for cigarette packages which is of pleasant appearance and high durability.

Another object is to provide a casing which is very simple in operation.

The objects of my invention are accomplished by the device described in the following specification and shown in the accompanying drawing in which

Fig. 1 shows a perspective view of a package of cigarettes enclosed in and held by the protective device according to my invention,

45 Fig. 2 is a perspective view of the device without the cigarette package, and

Fig. 3 is a bottom view of my invention.

My invention is preferably formed of a single, integral piece or plate of resilient material, such as celluloid, artificial resin, hard rubber, metal or the like. It consists of a back wall 2 which is preferably substantially plane. At each side edge of the back wall the sheet of material is bent to form side walls 4. These side walls are 55 bent inwardly through more than 90°, so as to be

to grip firmly the edges of a cigarette package. The side walls 4 are bent inwardly so as to incline towards each other and to form acute angles with the rear wall. In other words, the angle at 6 is formed during the manufacture so as to exert an inward stress on the side walls. At the front edges of the side walls, the plate is again bent inwardly to form two separate front wall portions 8. These preferably are substantially perpendicular to the side wall portions. The total width of the front wall portions is substantially equal to the width of the rear or back wall. It will be evident that when the device is not in use these front wall portions will overlap because of the inward inclination of the side walls.

The back portion 2 terminates at its lower edge in a flanged or bottom portion 10 of a width much less than the thickness of the package and container. By providing this relatively small bottom portion, the package of cigarettes will be held in place. Cigarettes can then easily be removed from the package by tearing off a portion of the wrapping at the top of the package and pressing the portion which is opposite the torn-off part and not covered by the flange. A supply of cigarettes may thus be pressed out of the package to such an extent as to be removed from the package without effort. The gripping action of the back portion 2 and the two front portions 8 is sufficient to allow the small pressure against the bottom of the package for removing cigarettes therefrom, without forcing the package out of the container. When a certain amount of cigarettes have been removed, the package will easily be crushed in the pocket of the consumer, when no stiffening device is provided to protect the package. The gripping action of the back and front portions of my container is so calculated that, while a certain amount of pressure is exerted upon the package, this pressure is not great enough to crush the package. The friction between the walls of the package and the inner surfaces of the gripping container is enough to hold even a practically empty package securely.

Another advantage of the flange-like bottom portion is that it increases the rigidity and stability of the container and particularly of the back wall, thus increasing the strength of the resilient gripping action of the back and front portions.

The splitting of the front wall into two parts 50 permits a package of cigarettes to be easily inserted in the container or removed therefrom.

As will be seen in the drawing, the corners 12 of the two front portions 8 are rounded off so as to prevent marring of the package as it 55

is being inserted and to avoid any scratching or tearing of the pocket.

The container can be manufactured of various kinds of materials, and by using an appropriate kind, various color effects can be produced or the casing can be provided with ornamentations pleasing to the eye. The solid appearance of the casing and such ornamentations or colored materials will give the device a pleasant aspect.

10 While I have shown and described my invention, I claim:

15 1. A protecting device for cigarette packages comprising a casing, said casing having a back portion, two side portions and two front portions, said front portions being normally inwardly inclined so as to produce a gripping action upon a cigarette package inserted within said casing.

20 2. A protecting device for cigarette packages comprising a casing, said casing having a back portion, two side portions, two front portions and a bottom portion, said front portions being inwardly inclined so as to produce a gripping action upon a cigarette package being inserted 25 within said casing, said bottom portion being of a width less than that of the container.

25 3. A protecting device for cigarette packages, comprising a casing having a back wall, side walls extending at an angle to said back wall, and normally pressed inwardly towards each other to assume normal positions at an acute angle to said back wall, and inwardly directed, 30 separate front wall portions extending inwardly from the front edges of the side wall portions and substantially at right angles thereto.

35 4. A protective device for cigarettes, comprising an integral casing formed of a single piece of resilient material, and comprising a back wall, side walls having normal positions at acute angles to said back wall and slightly inclined towards one another, said side walls being movable by pressure to positions substantially perpendicular to said back wall, and separate front

5 wall portions extending inwardly towards one another from the front edges of said side walls and substantially perpendicular thereto.

6. A protective device for cigarettes, comprising an integral casing formed of a single piece of resilient material, and comprising a back wall, side walls having normal positions at acute angles to said back wall and slightly inclined towards one another, said side walls being movable by pressure to positions substantially perpendicular to said back wall, and separate front wall portions extending inwardly towards one another from the front edges of said side walls and substantially perpendicular thereto, the combined width of said front wall portions being substantially equal to the width of said back wall.

10 6. A protective device for cigarettes, comprising an integral casing formed of a single piece of resilient material, and comprising a back wall, side walls having normal positions at acute angles to said back wall and slightly inclined towards one another, said side walls being movable by pressure to positions substantially perpendicular to said back wall, and separate front wall portions extending inwardly towards one another 15 from the front edges of said side walls and substantially perpendicular thereto, the combined width of said front wall portions being substantially equal to the width of said back wall, and an inwardly directed flange on the lower edge 20 of said back wall of a width less than that of the container.

25 7. A cigarette package holder, comprising an open ended frame proportioned to receive and substantially enclose a conventional package of cigarettes, having two opposed relatively wide side members and two opposed relatively narrow side members, one of the wide side members being split longitudinally along its medial portion, thereby providing two resilient wings having a 30 tendency to clamp inwardly upon the cigarette package.

35 IRVING FLORMAN.
